UNITED STATES PATENT OFFICE.

CHARLES S. MOSMAN, OF BRIDGEPORT, CONNECTICUT, ASSIGNOR TO THE JENNINGS BROTHERS MANUFACTURING COMPANY, A CORPORATION OF CONNECTICUT.

DESIGN FOR A BASE FOR A CRUCIFIX, CANDLESTICK, OR SIMILAR ARTICLE.

58,810.

Specification for Design.

Patented Aug. 30, 1921.

Application filed December 27, 1920. Serial No. 433,485. Term of patent 7 years.

To all whom it may concern:

Be it known that I, CHARLES S. MOSMAN, a citizen of the United States, residing at 138 Grove street, Bridgeport, county of Fairfield, State of Connecticut, have invented a new, original, and ornamental Design for a Base for a Crucifix, Candlestick, or Similar Article, (indicated as Case B,) of which the following is a specification, reference being had to the accompanying drawing, forming a part thereof.

In the drawing, Figure 1 is a side eleva-

tion of a base for a crucifix, candlestick, or similar article embodying my novel design: Fig. 2, an end elevation corresponding therewith; and

Fig. 3 is a skeleton plan view.

What I claim is—

The ornamental design for a base for a crucifix, candlestick, or similar article, substantially as shown.

In testimony whereof I affix my signature.

CHARLES S. MOSMAN.
